USING HEAVY OIL IN GAS MAKING.

1,418,782.

Specification of Letters Patent. Patented June 6, 1922.

Application filed July 2, 1920. Serial No. 393,663.

To all whom it may concern:

Be it known that we, OWEN B. EVANS and HARUTYUN G. TERZIAN, both citizens of the United States, residing at Philadelphia, in the county of Philadelphia and State of Pennsylvania, have jointly invented certain new and useful Improvements in Using Heavy Oil in Gas Making, of which the following is a specification.

10 The principal object of the present invention is to provide for the successful use, in the manufacture of carbureted water gas and oil gas, of heavy oil, meaning oil such as has a coke content sufficient to stop up or clog 15 the checker-brick upon which it is sprayed or otherwise introduced by forming a deposit of carbon or coke thereon or therein.

In the practice of this invention the comparatively cool coke or carbon deposit on or 20 at the entrance to the checker-brick is consumed or burned and removed by back blasting the apparatus with air which before reaching the comparatively cool deposit and in back traversing the checker-brick is sufficiently heated to burn the carbon or coke 25 deposit.

Accordingly the invention comprises the process of back blasting for the purpose indicated, as well as the process to be presently 30 described and finally claimed.

In further describing the invention reference will be made to the apparatus shown principally in elevation, but with parts broken away, on the accompanying drawings 35 and which is an ordinary carbureted water gas set and was chosen for convenience only.

The introduction of oil onto or at the entrance 1, of the checkerbrick, in the carbureter 3, occurs during the run and after, the 40 checkerbrick 2, has been heated during the blow in which ordinary or forward blasting occurs in the direction of from the generator 4, to the stack 5, of the superheater 6, and if the oil so introduced is heavy or has sufficient 45 coke content, a carbon deposit takes place on or at the entrance of the checkerbrick, sometimes extending down into the checkerbrick towards or to the bottom of the carbureter 3. Such a carbon deposit interferes with and 50 even prevents the normal practice of the gas making process. We remove this carbon deposit or coke from the entrance of the checkerbrick 1, by back blasting the appa-

ratus in the direction of from the fixing chamber stack 5, towards the generator 4. 55 By this back blasting the air is heated in traversing comparatively hot portions of the checkerbrick and ignites and consumes the comparatively cool carbon deposit or coke at the entrance of the checkerbrick. The back 60 blasting can be done from any of the air blast inlets 7, 8 or 9, and the products of combustion of the coke or carbon deposit can be led off by way of the generator fuel inlet 11, or by way of a stack 12, provided 65 on the carbureter for the purpose. The back blasting can be done while the gas making process is suspended for the purpose of cleaning the fire, and regular or forward blasting as from the blast inlets 10 and 13, can be alternated with the back blasting to temper 70 the heating of the checkerbrick. Any of the coke or deposit which may reach the bottom of the carbureter 3, may be removed through the cleaning door 14. By spraying the 75 heavy oil as from 15, in a number of comparatively large streams, the deposit occurs on the checkerbrick in separated spots, so that the back blast by passing between the spots has good access to the coke or deposit 80 for burning it off, and this is true in case the blast is introduced at 10, and led off at 5, which is possible when the carbon deposit at the top of the carbureter happens to be, at 85 the time, hot.

The wider the spaces between the bricks the longer it will take for the deposit from the oil to choke the checkerbrick, so that it is well to space the bricks quite wide apart and in this way assure a passage for the 90 back blast.

From the foregoing description of one application of the invention in connection with the described apparatus it will be obvious that in one of its aspects the invention consists in providing for the use of heavy oil by permitting it to deposit carbon on the checkerbrick and then consuming the deposit by blasting it with previously heated air.

We claim:

1. The process of using heavy oil in the manufacture of gas which consists in gasifying heavy oil by introducing it onto pre-heated checkerbrick thereby forming a carbon deposit on the checkerbrick, and consuming said deposit by back blasting the check- 100
105

erbrick with air which is heated by the checkerbrick before reaching the deposit, substantially as described.

2. The process of using heavy oil in the manufacture of gas which consists in gasifying heavy oil by introducing it onto checkerbrick pre-heated by forward blasting, back blasting the checkerbrick to consume the carbon deposit from the oil, and alternately 5 back and forward blasting to temper the heat, of the checkerbrick, substantially as described.

3. The process of using heavy oil in the manufacture of gas which consists in gasifying heavy oil by introducing it in spots onto 10

the preheated checkerbrick thereby forming spaced carbon deposits on the checkerbrick, and consuming said deposits by back blasting the checkerbrick with air which is heated by the checkerbrick before reaching the de- 20 posit, substantially as described.

4. The process of using heavy oil in the manufacture of gas which consists in gasifying heavy oil by introducing it to preheated checkerbrick thereby forming a carbon de- 25 posit on the checkerbrick, and consuming said deposit by blasting it with previously heated air.

OWEN B. EVANS.
HARUTYUN G. TERZIAN.

DISCLAIMER

1,418,782.—*Owen B. Evans and Harutyun G. Terzian, Philadelphia, Pa. USING HEAVY OIL IN GAS MAKING.* Patent dated June 6, 1922. Disclaimer filed September 16, 1931, by the assignee, *The United Gas Improvement Company*.

Therefore, disclaims: The process of using heavy oil in the manufacture of gas specified in each of the four claims, except in the manufacture of carbureted water gas.
